(57) **CLAIM**

We claim the ornamental design for a foldably constructed pallet bottom, as shown and described.

DESCRIPTION

FIG. 1 is an isometric view of a foldably constructed pallet bottom showing our new design, shown in condition of use. FIG. 2 is an isometric view of the foldably constructed pallet bottom of FIG. 1 with the pallet top removed.

FIG. 3 is a top plan view of the foldably constructed pallet bottom of FIG. 2.

FIG. 4 is a bottom plan view of the foldably constructed pallet bottom of FIG. 2.

FIG. 5 is a front elevation view of the foldably constructed pallet bottom of FIG. 2.

FIG. 6 is a rear elevation view of the foldably constructed pallet bottom of FIG. 2.

FIG. 7 is a left side elevation view of the foldably constructed pallet bottom of FIG. 2; and,

FIG. 8 is a right side elevation view of the foldably constructed pallet bottom of FIG. 2.

The dashed lines in FIG. 1 illustrate a pallet top for environment and form no part of the claimed design. The dashed lines in FIGS. 2 and 3 illustrate portions of the foldably constructed pallet bottom that form no part of the claimed design.
